UNITED STATES PATENT OFFICE.

PHILIP F. EDDY, OF PROVIDENCE, RHODE ISLAND, ASSIGNOR TO DUTEE W. FLINT OIL COMPANY, INCORPORATED, OF PROVIDENCE, RHODE ISLAND, A CORPORATION OF RHODE ISLAND.

DESIGN FOR A SIGNPOST.

Application filed January 28, 1925. Serial No. 12,170. Term of patent 14 years.

To all whom it may concern:

Be it known that I, PHILIP F. EDDY, a citizen of the United States, residing at the city of Providence, county of Providence and State of Rhode Island, have invented a new, original, and ornamental Design for a Signpost, reference being had to the accompanying drawing, forming a part thereof.

The figure is a side elevation of a sign post, showing my new design.

I claim:

The ornamental design for a signpost, as shown.

PHILIP F. EDDY.
